(57) CLAIM

The ornamental design for a display screen or portion thereof with icon, as shown and described.

DESCRIPTION

The FIGURE is a front view of a display screen or portion thereof with icon showing the new design.

The broken lines around the FIGURE show a display screen or portion thereof which forms no part of the claimed design. Broken lines within the FIGURE show portions of the icon which form no part of the claimed design.

1 Claim, 1 Drawing Sheet
